UNITED STATES PATENT OFFICE

121,809

DESIGN FOR A PLATE OR SIMILAR ARTICLE

Marcelline Goubler, Chicago, Ill., assignor to Mayer China Company, Beaver Falls, Pa., a corporation of Pennsylvania

Application June 1, 1940, Serial No. 92,727

Term of patent 14 years

To all whom it may concern:

Be it known that I, Marcelline Goubler, a citizen of the United States, residing at Chicago, Illinois, have invented a new, original, and ornamental design for a Plate or Similar Article, of which the following is a specification, reference being had to the accompanying drawing, forming part thereof.

The drawing is a top plan view of a plate showing my new design.

The dominant feature of the design is the surface ornamentation appearing on the article, and while shown applied to a plate, said ornamentation is intended to be applied to other similar articles.

I claim:

The ornamental design for a plate or similar article, substantially as shown and described.

MARCELLINE GOUBLER.
